UNITED STATES PATENT OFFICE.

GEORGE C. BLACKMORE, OF NEWARK, NEW JERSEY.

DESIGN FOR A HEATING-BOILER.

SPECIFICATION forming part of Design No. 19,455, dated December 3, 1889.

Application filed August 16, 1889. Serial No. 321,043. Term of patent 3½ years.

To all whom it may concern:

Be it known that I, GEORGE C. BLACKMORE, a citizen of the United States, residing at Newark, Essex county, New Jersey, have invented a certain new and useful Design for a Heating-Boiler, fully described and represented in the following specification and the accompanying drawings, forming a part of the same.

10 This invention relates to a new design for such water-heating boilers as are provided with several horizontal series of tubes, a fire-box being arranged beneath the tubes, and the separate series being superposed one above another.

15 The essential feature of the design consists in an arch of water-tubes having interspaces between the same over the fire-box.

Figure 1 is a vertical section through the 20 boiler transverse to the tubes on line x x in Fig. 2; and Fig. 2 is a plan of the second series of tubes above the fire-box.

a are the tubes of the lowest series, disposed only at the sides of the boiler, with a wide interspace *a'*.

25

b are the tubes of the second series, and *c*, *d*, and *e* those of the three upper series, superposed upon the two lower.

f is the fire-box, and *g* the grate.

By reference to the drawings it will be 30 seen that the central tubes *b* form the top of the arch, and the tubes *a* form its sides.

Having thus set forth my invention, what I claim herein is—

The design for a heating-boiler shown and 35 described herein.

In testimony whereof I have hereunto set my hand in the presence of two subscribing witnesses.

GEORGE C. BLACKMORE.
